HAIR-TREATING COMB

Mario G. Usai, East Paterson, N. J.

Application October 4, 1946, Serial No. 701,107

7 Claims. (Cl. 132—12)

1

This invention relates to implements for combing the hair and particularly to those which include means for coloring the hair during the combing.

The improved implement, including a comb which itself includes the usual elongated back and row of aligned teeth projecting therefrom with the points of the teeth all lying in substantially the same plane, is constructed in a novel way so that the user may use the implement simply to comb the hair or, by simple manipulation, use the implement so that during the combing the hair will be colored. For these purposes the comb is formed with a longitudinal cylindrical bore, and in and fitting this bore is a device for dispensing color to the hair, the same being rotative in and around the axis of the bore into and out of the position in which the color will be so dispensed. So much, generally stated, is known, as by the Ensor Patent No. 924,048, in which case the back of the comb is formed with ports leading from said bore to the spaces between the teeth and said device includes a cylinder fitting and rotative in the bore and containing a liquid-absorbent material and itself having ports adapted to deliver the liquid to the first-named ports when the cylinder is in a given rotative position. In this case the coloring substance must be a liquid which will more or less freely drain through the ports to reach the hair being combed, thus rendering the device untidy and likely to color the user's hands. According to my invention the construction is such that in the combing operation the hair directly contacts the color-dispensing medium, which means that the same may be a solid (acting to impart color after the manner of graphite, for instance) or a fibrous mass charged with liquid but not of the free-flowing type.

In the drawing.

Figs. 1, 2 and 3 illustrate one form of the improved implement.

Fig. 1 showing the comb and the rotary device each partly broken away at intervals and each partly in side elevation and partly in section;

Fig. 2 being a sectional view on line 2—2, Fig. 1, and

Fig. 3 being a right-hand end elevation of the implement;

Fig. 4 is an enlarged plan view of a modified form of the cylinder of said device before parts thereof are deformed to provide bearings;

Fig. 5 shows the latter device partly in elevation and partly in section on line 5—5 of Fig. 4;

2

Fig. 6 is a section of the implement including such device and on line 6—6 of Fig. 5;

Fig. 7 is a plan view of a color-dispensing medium that may be used with the cylinder of Fig. 5; and

Fig. 8 is a perspective view on a reduced scale of a color-dispensing medium that may be used with the cylinder of Figs. 1 to 3.

In Figs. 1 to 3 a comb is formed by an elongated back 1 and the row of aligned parallel teeth 2 projecting laterally from the back with their points lying all in the same plane. The comb is formed with a longitudinal cylindrical bore 3 open at the right hand end. This bore is formed partly in the back 1 and partly in the teeth 2, but so that its diameter in a plane perpendicular to the plane in which the teeth extend from the back is wholly within the latter; this bore is thus in communication with the spaces between the teeth, as at 4 in Fig. 1.

In the bore and fitting the same is a rotative cylinder 5 having its right-hand end protruding and formed with a knob 6, the cylinder having a longitudinal slot 7 of a width less than half the diameter of the cylinder. In Figs. 1 and 2 this cylinder is shown filled with a color-dispensing medium 8, as any fibrous material charged with some dispensable non-free-flowing coloring liquid. This medium being itself generally cylindrical protrudes through slot 7, and, when the device comprising it and the cylinder 5 is in the position shown, it reaches into that portion of the bore which exists formed in the teeth, whereby when the implement is used to color the hair during combing the medium 8 is exposed to direct contact with the hair strands reaching between the teeth. When the implement is to be used only for combing, said device is turned by the knob 6 to reversed position.

In place of the color-dispensing medium 8 a stiff foil or sheet 9 coated, like any ordinary carbon paper, on its outer surface with a dispensable coloring substance, may be rolled to a diameter to fit the cylinder snugly and be incorporated therein. Such sheet is shown in Fig. 8.

In place of the device formed by the cylinder 5 and a color-dispensing medium such as I have above described, a device such as Figs. 4 to 7 show may be used. Here the cylinder, having a knob 11 at one end, is formed with longitudinal slots 12, with longitudinally projecting ears 13 initially left at the ends of one slot. The ears are bent inwardly as shown in Fig. 5 and each has bearing holes, as 14, for the trunnions of a pair of rollers 15 each of some absorbent solid

material charged with dispensable coloring substance. Or, instead of a pair of such rollers, there may be only one, as 16, having its trunnions journaled in centering holes, as 17, of the ears.

In all the forms shown the bore is interrupted by the spaces between the teeth of the comb and it is occupied by a cylindrical device in and fitting and rotative in the bore around the axis thereof, and said device has its perimeter exposed by said spaces. Further, in a transverse zone of said device (here of a width approximating its length) opposed to said spaces, at least one segment of its perimeter is color-dispensing (as where, for example, the medium 8 in Figs. 1 to 3 is exposed by the slot 7 of cylinder 5) and another segment thereof (formed in Figs. 1 to 3 by the unslotted portion of the cylinder) is blank—by which I mean not disposed to dispense color. When the device is rotated either the color-dispensing or the blank segment will be exposed to said spaces, thus to expose the hair or shield it from the coloring substance.

Having thus fully described my invention, what I claim is:

1. A comb comprising an elongated back, a row of aligned teeth projecting from the back with their points substantially in the same plane, the comb having a cylindrical bore extending longitudinally thereof and located wholly therewithin and predominantly within the back, the bore intersecting the spaces between the teeth over a minor portion of its cross-sectional area, an elongated cylindrical member positioned coaxially within the bore, the surface of the cylindrical member having a non-color dispensing cylindrical zone of substantial width located parallel to the axis of the cylindrical member and extending throughout substantially the length of the row of teeth, the cylindrical member having in its surface an elongated color dispensing segmental portion of a substantial width and lying parallel to the axis of the cylindrical member, such color dispensing segmental portion extending throughout substantially the length of the row of teeth, and means to rotate the cylindrical member about its axis.

2. A comb comprising an elongated back, a row of aligned teeth projecting from the back with their points substantially in the same plane, the comb having a cylindrical bore extending longitudinally thereof and located wholly therewithin and predominantly within the back, the bore intersecting the spaces between the teeth over a minor portion of its cross-sectional area, an elongated cylindrical member positioned coaxially within and rotatable in the bore, the surface of the cylindrical member having a non-color dispensing cylindrical zone of substantial width located parallel to the axis of the cylindrical member and extending throughout substantially the length of the row of teeth, the cylindrical member having in its surface an elongated color dispensing segmental portion of a substantial width and lying parallel to the axis of the cylindrical member, such color dispensing segmental portion extending throughout substantially the length of the row of teeth, and means to rotate the cylindrical member about its axis.

3. A comb comprising an elongated back, a row of aligned teeth projecting from the back with their points substantially in the same plane, the comb having a cylindrical bore extending longitudinally thereof throughout the length of the row of teeth, said bore being located wholly within the comb and predominantly within the

back, the bore intersecting the spaces between the teeth over a minor portion of its cross-sectional area, a hollow elongated cylindrical container positioned coaxially within, closely fitting, and rotatable in the bore, the cylindrical container having a length substantially equal to that of the bore, the side wall of the cylindrical container having an imperforate cylindrical zone of a width exceeding the width of the area of intersection between the bore and the spaces between the teeth, and of a length at least equal to the length of the row of teeth, the cylindrical container also having a longitudinal slot of substantial width through its side wall, the slot lying parallel to the axis of the cylindrical container, a color dispensing medium within the container, and means to rotate the cylindrical container about its axis.

4. A comb comprising an elongated back, a row of aligned teeth projecting from the back with their points substantially in the same plane, the comb having a cylindrical bore extending longitudinally thereof and located wholly therewithin and predominantly within the back, the bore intersecting the spaces between the teeth over a minor portion of its cross-sectional area, a hollow elongated cylindrical container positioned coaxially within, closely fitting, and rotatable in the bore, the cylindrical container having an imperforate cylindrical zone, of a width exceeding the width of the area of intersection between the bore and the spaces between the teeth, located parallel to the axis of the cylindrical container and extending throughout substantially the length of the row of teeth, the cylindrical container having a longitudinal slot through its side wall of a substantial width and parallel to the axis of the cylindrical container, a resilient absorbent pad within the container, and means to rotate the cylindrical member about its axis.

5. A comb comprising an elongated back, a row of aligned teeth projecting from the back with their points substantially in the same plane, the comb having a cylindrical bore extending longitudinally thereof throughout the length of the row of teeth, said bore being located wholly within the comb and predominantly within the back, the bore intersecting the spaces between the teeth over a minor portion of its cross-sectional area, a hollow elongated cylindrical container positioned coaxially within, closely fitting, and rotatable in the bore, the cylindrical container having a length substantially equal to that of the bore, the sidewall of the cylindrical container having an imperforate cylindrical zone parallel to the axis of the cylindrical container and of a width exceeding the width of the area of intersection between the bore and the spaces between the teeth, and of a length at least equal to the length of the row of teeth, the cylindrical container also having a longitudinal slot of substantial width through its side wall, the slot lying parallel to the axis of the cylindrical container, a resilient absorbent pad substantially filling the cavity within the container, and means to rotate the cylindrical member about its axis.

6. A comb comprising an elongated back, a row of aligned teeth projecting from the back with their points substantially in the same plane, the comb having a cylindrical bore extending longitudinally thereof throughout the length of the row of teeth, said bore being located wholly within the comb and predominantly within the back, the bore intersecting the spaces between the teeth over a minor portion of its cross-sec-

tional area, a hollow elongated cylindrical container positioned coaxially within, closely fitting, and rotatable in the bore, the cylindrical container having a length substantially equal to that of the bore, the sidewall of the cylindrical container having an imperforate cylindrical zone parallel to the axis of the cylindrical container and of a width exceeding the width of the area of intersection between the bore and the spaces between the teeth, and of a length at least equal to the length of the row of teeth, the cylindrical container also having a longitudinal slot of substantial width through its sidewall, the slot lying parallel to the axis of the cylindrical container, a color dispensing medium within the container, and means to rotate the cylindrical container about its axis, said color dispensing medium comprising a rolled foil in and fitting the cylindrical container, said foil having its outer surface composed of color-dispensing substance.

7. A comb comprising an elongated back, a row of aligned teeth projecting from the back with their points substantially in the same plane, the comb having a cylindrical bore extending longitudinally thereof throughout the length of the row of teeth, said bore being located wholly within the comb and predominantly within the back, the bore intersecting the spaces between the teeth over a minor portion of its cross-sectional area, a hollow elongated cylindrical container positioned coaxially within, closely fitting, and rotatable in the bore, the cylindrical

container having a length substantially equal to that of the bore, the sidewall of the cylindrical container having an imperforate cylindrical zone parallel to the axis of the cylindrical container of a width exceeding the width of the area of intersection between the bore and the spaces between the teeth, and of a length at least equal to the length of the row of teeth, the cylindrical container also having a longitudinal slot of substantial width through its side wall, the slot lying parallel to the axis of the cylindrical container, a color dispensing medium within the container, and means to rotate the cylindrical container about its axis, said color dispensing medium comprising a roller journaled in the cylindrical container with its axis parallel with the axis of the cylindrical container, the periphery of said roller protruding through the slot in the cylindrical container, said roller being formed as a solid material charged with a dispensable coloring substance.
